LOW PRESSURE SPRAYING APPARATUS

Filed Feb. 29, 1928

UNITED STATES PATENT OFFICE

EUGENE F. MARTINET, OF CLEVELAND, OHIO, ASSIGNOR TO THE P. A. GEIER COMPANY,
OF CLEVELAND, OHIO, A CORPORATION OF OHIO

LOW-PRESSURE SPRAYING APPARATUS

Application filed February 29, 1928. Serial No. 258,069.

My invention relates to improvements in low-pressure spraying-apparatus, and more particularly to such an appliance as is adapted for use in connection with, and as a blower attachment for the portable type of a suitable electric suction cleaner. The primary object of my invention is the production and proper attachment of a device that will effectively spray or distribute a wide variety of liquids or powders with the relatively low pressure attained by the electrically driven fan, primarily, of a modern suction cleaner.

I am aware that previously the blower attachment of suction cleaners has been applied or attempted to be applied to various uses, but I believe that the apparatus hereinafter described and shown in the drawings is the first successfully to meet the varied practical requirements of a low-pressure spraying mechanism for powders or liquids, adapted for general household use.

A principal requirement of an appliance of this class is the provision of a substantially straight and relatively large conduit extending directly from the fan chamber to the spraying nozzle. Such a conduit is necessary in connection with a low-pressure fan, not only for the purpose of reducing interior friction and avoiding eddy currents therein, but also to afford an equalizing chamber and convert the air currents into a steady blast at the spraying nozzle.

Another requirement discovered by me in connection with apparatus of this class is the desirability of providing a wide range of adjustment for using liquids of widely different specific gravities. For this purpose the bore of the spraying nozzle is of tubular form and material inner diameter, while the liquid nozzle associated therewith is provided with an adjustment to position the tip in various planes adjacent to the axis of the elongated spraying nozzle. In addition to this there is provided an air-pressure connection to the container adapted to facilitate the discharge of heavy liquids in the well known manner. This connection has its own regulating valve and a shut-off valve which is adapted to close prior to the closing of the shut-off valve member for the spraying nozzle.

Preferably these members are mounted as a unit upon the cover of the liquid container, while the integral air chamber admirably serves as a handle for applying the spray. These and other details of construction and operation may best be explained by making reference to the accompanying drawings.

Figure 1 of said drawings illustrates in side elevation, centrally broken away, the assembled apparatus embodying my instant improvement,

Fig. 2 is a fragmentary rear view of the unitary mounting of the spraying members upon the cover,

Fig. 3 is a vertical sectional view thereof, and

Fig. 4 is a view in side elevation, partially broken away and in section, showing the jar with the cover and spraying attachments mounted thereon, with details of the air-pressure connection and its regulating valve.

Fig. 5 is a fragmentary view in side elevation, and Fig. 6 is a plan view principally illustrating a modification of the air vent provided with automatic closure means.

The scale of Figs. 2, 3 and 4 is materially larger to bring out certain details, and the same character of reference is applied throughout all of the figures to designate similar parts therein shown.

Practically all of the modern portable electric suction cleaners are now provided with a removable dust bag and with a hose, usually employed with auxiliary brushes or suction nozzles. The hose may also be used in connection with a blower attachment and the preferred embodiment adapted for the instant improvement is illustrated in Fig. 1 of the drawings. Therein the electric suction cleaner is shown minus the customary dust bag; the outlet *a'* of the fan chamber *a* extending therefrom at an easy angle to accommodate the removable hose *b*, preferably of but moderate length, extending directly to the spray attachment. The free end of said hose fits upon a straight tubular handle member *c* which approximates the relatively large inner diameter of the hose to avoid frictional resistance and eddies in the air currents.

This handle member thus forms the ex-

tremity of an elongated and substantially straight conduit which affords a low back-pressure for the air controllably escaping from the tubular spraying nozzle of material 5 and substantially uniform inner diameter, as shown at c' . A secondary vent c'' , the purpose of which appears later, together with the opening to nozzle c' , are respectively controlled by the sliding valve-plate d normally 10 held before the respective openings on its depressible stem d' , by means of the coiled spring d'' . The openings c' and c'' are formed in the plane-surfaced end member x for the tubular member c .

15 A glass jar e forms the liquid container and is normally closed by its screw cap e' which mounts the handle member, nozzle and valve by means of an L-shaped bracket e'' screwed to said cap. An air vent e^3 is provided in 20 said cap, together with a controllable pressure vent from the air conduit, and an adjustable liquid nozzle with its tube extending to the bottom of the jar, are shown in Figs. 3 and 4. The tip f of said liquid nozzle, 25 terminating the supply tube f' , which is suitably threaded, has a thumb nut f'' adapted to secure said tip in varying planes with respect to the axis of nozzle c' .

This arrangement of a spraying nozzle of 30 elongated uniform bore and large inner diameter not only affords an adjustment of wide range for the liquid nozzle in order to adapt it for use with liquids of different consistencies and specific gravities, but the discharge of air from the air-pressure chamber, 35 afforded interiorly of the handle member c , encloses and directs the sprayed liquid interiorly of the air column. By adjusting the nozzle f higher or lower, with respect to the 40 air column of material diameter evenly directed from spraying nozzle c' , different materials may be employed and applied and varying effects obtained.

45 Augmenting this, however, I also provide an air-pressure connection g upon the top of the jar which is afforded complete regulation by the needle valve g' , serving likewise as a complete shut-off. It will be observed in 50 Figs. 2 and 3 that the valve plate d is loosely mounted upon its stem d' by a yoke and groove connection and that the valve plate d serves normally to close the openings to the connection g and spraying nozzle, respectively at c'' and c' , Fig. 2. This sliding valve 55 member is so constructed as to afford initial closure of the vent c'' by means of the extension d^3 before the air supply to the nozzle is completely cut off. Thus, the added pressure in the jar e , assuming that valve g' is open, 60 will be relieved through the vent e^3 before the spraying nozzle ceases to act, so that there will be no excess of liquid forced from the jar with the intermittent use of the spraying nozzle.

65 Moreover, the loose mounting of the plate

valve d on the stem d' enables air pressure in the member c to adequately seat the valve d against the plane-surfaced end member x , without requiring the members d and x to be accurately machined or ground in fabricating 70 the same. Also, the loose mounting of the valve d on the stem d' enables the valve to properly seat against the plane-surfaced end member x without requiring the holes in which the stem d' is slidably journaled to be accurately located with respect to the surface of the member x when the device is being fabricated. Thus, the parts may be economically manufactured without requiring expensive operations to be performed upon the 80 same.

Instead of employing the simple vent e^3 for relieving the air pressure or maintaining atmospheric pressure, approximately, within jar e , I may also provide the modification 85 disclosed in Figs. 5 and 6. Therein the air vent is of much larger area, as afforded by the normally open tube h . There is provided at the top of stem d' a closure member in the form of a spring h' which lies above the 90 top of tube h and upon the depression of said stem to open the spraying nozzle, this spring is pressed down upon the top of said tube and substantially closes the same. This elevated air vent h not only affords closure 95 means not liable to be affected or fouled by the paint or enamel, but also contributes to the avoidance of slopping or spilling the contents of the jar. By automatically closing said air vent, a materially lower working 100 pressure may be availed of for spraying operations.

Spraying apparatus commonly in use employs a relatively high air pressure and a restricted orifice at the spraying nozzle. With 105 the employment of a low pressure fan unit, however, different conditions obtain, and a larger volume of air preferably is used. Moreover, the intermittent impulses imparted to the air currents by a rapidly rotated fan require a relatively large conduit and air chamber in order to avoid eddy currents, friction and inequalities in pressure at the spraying nozzle, as well as a direct transmission line without abrupt turns or 110 constrictions from the fan chamber to the spraying nozzle.

In an appliance of this character it is important that the apparatus shall be of the simplest and most economical type, yet affording a capacity for using a wide range of materials, both powdered and liquid, if household requirements shall be met. The foregoing features, it will be seen, are adequately provided in the apparatus embodying 115 my instant improvements, while said apparatus is very easily operated and is not liable to get out of order.

Having now described the preferred apparatus embodying my invention, I claim as new 120

and desire to secure by Letters Patent, the following:

1. In a spraying attachment, the combination with a liquid container and its protruding liquid tube, of walls forming an air-pressure chamber, there being an opening in one of the chamber walls and a spraying nozzle associated with the terminal of the liquid tube and communicating through said opening with the air-pressure chamber, there being a second opening in one of the chamber walls and means communicating through the second opening between the air-pressure chamber and the container, and valve means for closing said openings mounted for movement adjacent the openings and adapted to close said second opening prior to the closing of the first opening.
2. In a spraying attachment, the combination with a liquid container and its protruding liquid tube, of walls forming an air-pressure chamber, there being an opening in one of the chamber walls and a spraying nozzle associated with the terminal of the liquid tube and communicating through said opening with the air-pressure chamber, there being a second opening in one of the chamber walls and means communicating through the second opening between the air pressure chamber and the container, and a plate valve for closing said openings slidably mounted for movement transversely of the axes of said openings and adjacent thereto and adapted to close said second opening prior to closing the first opening.
3. In a spraying attachment, the combination with a liquid container and its protruding liquid tube, of walls forming an air-pressure chamber, there being an opening in one of the chamber walls and a spraying nozzle associated with the terminal of the liquid tube and communicating through said opening with the air-pressure chamber, there being a second opening in one of the chamber walls and means communicating through the second opening, between the air-pressure chamber and the container, a valve in said communicating means, and valve means for closing said openings mounted for movement adjacent the openings and adapted to close said second opening prior to the closing of the first opening.
4. In a spraying attachment, the combination of a liquid container having a liquid supply nozzle with an air-pressure chamber having adjacent openings to a spraying nozzle and to an air-pressure connection to said container, of a unitary sliding valve-member having portions respectively positioned initially to close the opening to said connection and thereafter the opening to the nozzle upon movement of the valve to normal position, an actuating plunger for the valve member, a spring cooperating with the plunger normally operative to maintain the valve mem-

ber in position to close said openings, and a spraying nozzle connected to said spraying nozzle opening and cooperating with said liquid supply nozzle.

5. In a spraying attachment, the combination of a liquid container having a liquid supply nozzle with an air-pressure chamber provided with a plane-surfaced end member having adjacent openings to a spraying nozzle and to an air-pressure connection to said container, of a unitary sliding plate valve member having portions respectively positioned initially to close the opening to said connection and thereafter the opening to the nozzle upon movement of the valve to normal position, an actuating plunger loosely mounting said valve member, a spring cooperating with the plunger normally operative to maintain the valve member in position to close said openings, and a spraying nozzle connected to said spraying nozzle opening and cooperating with said liquid supply nozzle.

6. In a spraying attachment, the combination with an air-pressure chamber of relatively large diameter closed by a plane-surfaced end member, of a spraying nozzle communicating with said chamber and connected to said end member, and an air-pressure connection communicating with said chamber and extending from said end member, a slideable plate valve member seating against said end member normally cutting off communication between said chamber and the spraying nozzle and air-pressure connection, a spring actuated plunger mounting said valve member, a liquid container mounting the chamber, nozzle, connection, valve and plunger and communicating with said connection, and a liquid tube protruding from the container adjacent to said nozzle.

7. In a spraying attachment, the combination with cylindrical walls forming an air-pressure chamber of relatively large diameter, of a spraying nozzle axially connected to said chamber walls, a liquid container, a liquid nozzle communicating with said container and located in aspirating relation with the spraying nozzle, an air-pressure connection from said chamber to the container independently of said nozzle, a unitary control valve for said nozzle and connection and closing the connection before closing the nozzle, an air vent for the container mounted thereon independently of said nozzle and said connection and elevated above the spraying nozzle, a plunger for the control valve, and a closure for the vent mounted upon said plunger.

In testimony whereof I do now affix my signature.

EUGENE F. MARTINET.
